UNITED STATES PATENT OFFICE.

EDWIN L. WHITE, OF BROOKLYN, NEW YORK, ASSIGNOR TO J. H. WHITE MANUFACTURING COMPANY, OF BROOKLYN, NEW YORK, A CORPORATION OF NEW YORK.

SOCKET CONNECTION FOR LIGHTING-FIXTURES.

1,233,829.

Specification of Letters Patent. Patented July 17, 1917.

Application filed February 7, 1917. Serial No. 147,048.

To all whom it may concern:

Be it known that I, EDWIN L. WHITE, a citizen of the United States, residing at the borough of Brooklyn, in the county of 5 Kings, city and State of New York, have invented an Improvement in Socket Connections for Lighting-Fixtures, of which the following is a specification.

My invention relates to socket connections 10 for the ends of tubes carrying the conductor wires in electric lighting fixtures. These connections have heretofore been made of a brass casting provided in the top with a threaded hole to receive the end of the tube, 15 and having at one side another smaller threaded opening into which is screwed a hollow exteriorly threaded stud with one end projecting to receive the lamp socket, there being a passage way between the two 20 openings for the conductor wires. These castings are heavy and the stud is liable to work loose or become detached in removing a socket. The object of my present invention 25 is to economize in the cost of such connections by greatly reducing the quantity of metal used; dispensing with the necessity for screwing the socket receiving stud into the body portion and preventing any possibility of the stud being turned when a 30 socket is removed from it.

The details of the invention are herein- 35 after particularly described.

In the accompanying drawing:

Figure 1, is a plan view of the shell or 40 body member.

Fig. 2, is an elevation of the inner member-removed from the shell.

Fig. 3, is a vertical central section showing the two members, connected together 45 ready for sale and use.

Fig. 4, is a plan view of the device with the members assembled, and

Fig. 5, is a side elevation showing the device connected with a bracket and having a 50 lamp socket attached.

Similar reference characters indicate like parts throughout the several figures of the drawing.

10, indicates a hollow globular body member open at the top and contracted at a pre-determined distance below its upper edge forming an internal annular shoulder 11.

In one side of this hollow member there is an opening 12, surrounded on the outer

surface of the body member by a boss 13. 55 This body member is formed of sheet metal.

14, denotes a metallic disk with upturned edge. This disk fits within the top of the body member 10, and rests upon the annular shoulder 11. 60

By means of a punch and die, a hole is punched in the center of the disk 14, forming a downwardly projecting tubular portion 15, which is afterward internally screw-threaded. 65

On one side of the disk 14, there is a downwardly inclined projection or arm 16, upon the lower end of which there is an exteriorly screw-threaded nipple 17, having a flange 18 at its junction with the arm 16. 70

The disk 14, tubular projection 15, arm 16, and nipple 17, are preferably formed of one piece of metal, the nipple being formed by means of a punch and die, in a manner similar to that in forming the projection 15, the exterior being threaded after its removal from the die by any suitable tool. The interior of the nipple is smooth and is curved outwardly at its junction with the flange 18 to leave a smooth rounding 80 surface at this point for the conductor wires to contact with.

The disk 14 is inserted in the top of the hollow body member 10, the disk being seated upon the annular shoulder 11, while the 85 nipple 17 passes through the opening 12 in the body member projecting therefrom. The upper edge of the body member 10 is then upset or turned inward over the upturned edge of the disk thus securely locking the 90 disk and nipple in position within the body, as shown in Figs. 3 and 4.

The device is now ready for attachment to a fixture and to receive a lamp socket, as illustrated in Fig. 5, in which 20, indicates 95 the tubular arm of a bracket or other fixture, the threaded end of which is screwed into the central threaded tubular projection 15, on the disk 14, the lamp socket 21, being screwed onto the projecting nipple 17, and 100 against the boss 13, which boss strengthens the shell 10, at the opening preventing any tendency to buckle the shell.

The conductor wires (not shown) pass into the hollow body 10, from the tubular 105 arm 20, and through the nipple 17, the interior of which being smooth and curved at its junction with the flange 18 as described,

there is no tendency to cut or injure the insulation on the wires.

By the employment of my invention there is a large saving in material, and cost of manufacture; the socket receiving nipple is securely held in proper position at all times and cannot be loosened or displaced in removing a socket, and the nipple provides a smooth interior which prevents injury to the conductor wires.

10 I claim as my invention:

1. A device of the character described, comprising a hollow body with an aperture in one side, a disk secured within said body, a nipple connected with said disk and projecting through said side aperture in the body, said disk having a threaded central opening for connecting the device to a lighting fixture.

20 2. A device of the character described, comprising a body shell open at the top and having an aperture in one side surrounded by an exterior boss, a disk secured within the top of said body and having a projecting 25 arm with a nipple upon its free end, said nipple projecting through said side aperture in the body, and said disk having a central opening to receive the end of an arm of a lighting fixture.

30 3. A device of the character described, comprising a hollow body open at the top with an internal annular shoulder adjacent

the top and an aperture in one side, a disk with upturned edge within said body and seated upon said annular shoulder, the upper edge of the body being turned over the upturned edge of said disk to secure it in position, a dependent arm extending from one side of said disk, an exteriorly threaded nipple connected to the free end of said arm and projecting through said aperture in the side of the hollow body, said disk having a central opening for receiving the end of a lighting fixture.

4. In a lighting fixture and in combination, a socket connection comprising a hollow body open at the top with an internal annular shoulder adjacent the top and an aperture in one side, a disk with upturned edge within said body and seated upon said annular shoulder, the top edge of the body being turned over the upturned edge of said disk to secure it in position, a dependent arm extending from one side of said disk, an exteriorly threaded nipple connected to the end of said arm and projecting through said aperture in the side of the hollow body, a lamp socket secured upon said projecting end of the nipple, said disk having a central threaded opening for connection with the fixture.

Signed by me this 29th day of January, 1917.

EDWIN L. WHITE.
